UNITED STATES PATENT OFFICE.

CARL F. HAUSSLER AND NICHOLAS W. PARK, OF PROVIDENCE, RHODE ISLAND, ASSIGNEES TO THE GENERAL FIRE EXTINGUISHER COMPANY, OF PROVIDENCE, RHODE ISLAND, A CORPORATION OF NEW YORK.

INDUCTOR FOR GAS BURNERS.

Application filed May 8, 1920. Serial No. 379,747.

To all whom it may concern:

Be it known that we, CARL F. HAUSSLER and NICHOLAS W. PARK, citizens of the United States, both residing at Providence, in the county of Providence and State of Rhode Island, have invented certain new and useful Improvements in Inductors for Gas Burners, of which the following is a specification.

10 This invention relates to improvements in inductors for gas burners. It is for convenience herein referred to in terms of air and ordinary illuminating gas used for heating, although it is applicable to the combination of any two gases for combustion. More particularly it relates to means for supplying air under pressure to the gas in such manner as to provide certain, adequate and properly proportioned supply for the combustion, especially in cases where the whole 20 of the air for combustion is to be supplied as "primary" air.

One object of the invention is to provide apparatus for obtaining such suitable coordination of air supply and gas supply in cases where the air is taken from any source under pressure and to do so by simple and inexpensive means. Another object is to provide such means which can be applied to an existing burner without extensive or expensive changes.

The objects are accomplished by providing means to produce an envelope of air under pressure about the burner pipe, with openings for the induction of air thereto from the envelope in jets whose rate is controlled by a valve which is mechanically and operatively connected with the gas valve. A gradual opening may be provided, corresponding to graduated opening of the gas valve, account being taken of the relative pressure of air in the envelope and gas in the pipe.

A specific embodiment of the invention is illustrated, in which the air envelope is constituted by a simple hollow cylinder enveloping the supply end of the burner pipe and, in the preferred form, enveloping also the gas valve, which cylinder is a continuation of the pipe through which air comes from the source of supply. If it be desired to improve the action of an atmospheric burner to which no supply of compressed air is conveniently available, the apparatus may include a sim-

ple blower whose delivery pipe constitutes the said air envelope. 55

The invention may be embodied in forms other than those herein described. It is intended that the patent shall cover, by suitable expression in the appended claims, whatever features of patentable novelty exist 60 in the invention disclosed. In the accompanying drawing,

Figure 1 is a medial section which may be considered to be an elevation through apparatus embodying the invention; 65

Figure 2 is a plan of a detail of the same, with the enveloping part removed.

Figure 3 is an end elevation of the same, in section on the line 3—3 of Figure 2.

Figure 4 is a side elevation of a modification; and 70

Figure 5 is a side elevation of another modification.

Referring to the drawings, 10 indicates a gas supply pipe leading through a cock 11 having handle 12 to a gas discharge orifice 13 at the supply end of a burner tube 14. The latter may be assumed to extend to the left from Figure 1, conducting air and gas ready for combustion to burner orifices (not shown) of any desired or suitable style. The burner tube is tightly closed by a tubular bushing or fitting constituting a sort of vestibule 15, within which is the gas inlet 13 and through the walls of which are openings 16 for air induction from the surrounding envelope of air contained within the cylindrical chamber 17. This chamber, as represented, consists of a tubular casting of relatively large diameter, closed at one end by a removable stopper or head 18 and at the other by an end wall. The latter is perforate, to accommodate the bushing which constitutes the vestibule piece 15. Through the sides of this chamber are two holes, one for the stem of the gas cock 12 and the other for the incoming gas pipe 10; and through the head 18 is the entrance for compressed air from a pipe 20. The chamber is conveniently arranged to receive the stem of the gas cock by providing a removable plate 17^a at its top having a sizable hole 17^b through which the stem of the cock 11 may pass with a sleeve 17^c fitting it and serving as a bearing for it and having a flange 17^d adapted to engage the inner side of the plate and pro-

105

vided with a screw on which a nut 17^e may be run up as a clamp against an outer face of this plate 17^a. The protruding parts and the openings for them may be otherwise arranged, or even may be omitted, as may be most convenient, suitable means of some sort being provided for the induction of compressed air to the chamber 17 and of gas to the cock 11. The vestibule bushing 15, in the form of the invention which is illustrated in the drawing, carries a cylindrical sleeve 21, which is adjustable and is placed and is movable so as to cover or uncover the induction inlets 16, which may be several in number, at intervals around. The sleeve 21 thus constitutes a valve whose arrangement for operation is best seen in Figure 2. A link 22 is provided for attaching it to an arm projecting for the purpose from the stem of the gas cock 11. The cylindrical valve 21 is so arranged that when the gas cock is in its closed position the holes are also in their closed condition; but so that with the turning of the gas cock the cylindrical valve 21 is moved exposing the holes 16 therein and thus making an opening through which air will flow in jets from the pressure envelope supply. These holes may be dimensioned and arranged so as to produce any desired degree of opening for air induction at each stage of opening of the gas cock 11 and will naturally be proportioned with regard to the pressure of air in the chamber 17, to limit the jetting of air therefrom into the vestibule to the desired effect. In arrangement illustrated they are holes of equal size drilled in an oblique row and slightly overlapping each other.

In the apparatus illustrated in Figure 1 the connection from an available supply of air under pressure is indicated by the pipe 20.

Figure 4 illustrates a modification in which in place of the disk wall 18 and air supply 20 there is substituted the discharge pipe 30 of an air blower 31 of any suitable type. The chamber 17 thus becomes practically a part of the discharge pipe 30 of the blower, it being contemplated that the blower be small and set close. Under these circumstances it is clear how the air propelled by the blower through the orifices 16 may constitute means for forcing the flame at the end of the burner, and may have injector action drawing more gas through the gas discharge 13, and so increasing the flame. The predetermination of induction at all stages of gas valve opening, resulting from the working pressure of air, makes a notable increase of efficiency over some apparatus now in common use.

Figure 5 illustrates another modification, which for convenience is illustrated as being of the type of Figure 1 in that it has connection for air from a remote compressor.

In this the chamber 17' does not cover the gas pipe and valve 10, 11, but the end stopper or head 18' fits upon the cylindrical air valve 21.

The construction and operation of the apparatus is independent of particular gaseous material with which it is worked, the terms "gas" and "air" herein being typical of any two gases which unite in combustion and not constituting limitations of the metallic structure nor of the range of gaseous material with which it may be used.

It will be observed that the vestibule 15 is essentially a part of the burner tube 14 although in the structural form represented it is a separate piece of metal, being conveniently formed as a sort of bushing which helps clamp together the burner tube and the enclosing air chamber 17. It is therefore in the claims spoken of as being a part of the tube, meaning the burner tube; and it would not be the less so if there happened to be some restriction or some greater length or different shape between it and the place where the burning actually occurs for its function is to provide means for suitable co-ordination between the gas supply and the air supply, prior to combustion, by simple means where the air is under pressure.

We claim as our invention:

1. Apparatus for mutually adapting atmospheric air and gas for combustion, comprising the combination, with a pipe supplying the gas under pressure and having restricted discharge, of a burner tube receiving the discharge of the gas supply pipe and connected thereto by a tight joint excluding atmospheric air; an air chamber through which all of the primary air passes, enveloping a part of the burner tube and having restricted discharge opening into the burner tube; and means to compress atmospheric air and to supply it under pressure to the enveloping chamber; whereby, by taking account of the relative pressures and discharge openings, and of the expansion of gas and air therefrom into the burner tube, the relative constituents of gas and air in the mixture can be adapted for perfect combustion according to a predetermined standard.

2. Apparatus for mutually adapting atmospheric air and gas for combustion, comprising the combination, with a pipe and valve supplying the gas under pressure, of a burner tube connected to the gas supply pipe by a tight joint excluding atmospheric air; an air chamber through which all of the primary air passes, enveloping a part of the burner tube and having discharge into the burner tube with valve graduating its opening; means to compress atmospheric air and to deliver it under pressure to the chamber; and interconnection between the two valves, whereby the sizes of the discharge openings vary simultaneously and the expansion of

gas and air therefrom into the burner tube maintains the relative constituents of gas and air in the mixture approximately in predetermined proportions.

- 5 3. Apparatus for mutually adapting atmospheric air and gas for combustion, comprising the combination, with a pipe and valve supplying the gas under pressure, of a burner tube connected to the gas supply pipe 10 by a tight joint excluding atmospheric air; a rotary blower, through which all of the primary air passes, having a discharge pipe which envelopes a part of the burner tube; there being in the burner tube an opening 15 with valve permitting flow of air from the blower discharge tube into the burner tube; interconnection between the two valves, whereby they move simultaneously and the expansion of gas and air therefrom into the 20 burner tube maintains the relative constituents of gas and air in the mixture approximately in predetermined portions.
4. An inductor comprising a burner tube having an axial inlet for gas and a peripheral inlet for air; an enveloping tube adapted to hold air under pressure at said peripheral inlet; and interconnected means for controlling said inlets simultaneously, including a tubular valve slidable along said burner 25 tube to open or close said peripheral inlet.
5. An inductor comprising a burner tube having an inlet for gas under pressure; a peripheral inlet for air under pressure further along the tube; a sleeve valve movable 30 over the tube to close said peripheral inlet; a chamber enveloping said peripheral inlet and sleeve and adapted to hold air under pressure; and interconnected means for controlling flow of supplies to said two inlets.
- 40 6. An inductor comprising a tube adapted to conduct mixed gas and air to a burner; a chamber fixed against the inlet end of the tube; a flanged bushing within the chamber and passing through its wall into the end of the tube clamping these three parts together;
- 45

there being openings into said bushing for admission of gas under pressure and for admission of air under pressure, the latter being through the sides of the bushing from said chamber and having means movable 50 over the outside of the bushing to close the opening gradually; gas control means for closing the gas supply gradually; and interconnection between said closing means whereby their action is co-ordinated.

55 7. An inductor comprising a chamber and means for admitting compressed air thereto; a gas pipe entering the chamber and forming a conduit therein for gas; a tube having a portion within the chamber, closed except for admission openings for said gas from the conduit and for said air within the chamber, and leading out from the chamber to conduct away the mixed gas and air; and interconnected control means for the air and 60 gas passages into said tube.

65 8. An inductor comprising a chamber and means for admitting compressed air thereto; a gas pipe entering the chamber and forming a conduit therein for gas; a tube having a portion within the chamber, closed except for admission openings for said gas from the conduit and for said air within the chamber, and leading out from the chamber to conduct away the mixed gas and air; a cock in 70 the gas pipe within the chamber; a movable plate comprising a part of the chamber wall through which the stem of the gas cock protrudes; a cylindrical bearing for the stem, surrounding the stem and secured to said 75 plate, preventing air leakage from the chamber; and a movable part on the tube adapted to close the air passage from the chamber into the tube and operatively connected with said gas cock within the chamber.

80 Signed at Providence, Rhode Island, this fourth day of May, 1920.

CARL F. HAUSSLER.
NICHOLAS W. PARK.
